UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

DRAFT-RIGGING BACKSTOP.

Application filed December 30, 1921. Serial No. 525,872.

To all whom it may concern:

Be it known that I, DONALD S. BARROWS, a citizen of the United States, residing at Rochester, in the county of Monroe and State of New York, have invented certain new and useful Improvements in Draft Rigging Backstops; and I do hereby declare the following to be a full, clear, and exact description of the invention, such as will enable others skilled in the art to which it appertains to make and use the same.

My invention relates to draft rigging backstops such as are secured between the center sills or draft sills of a railway car for the purpose of transmitting to the car under-frame the buffing shocks to which the draft rigging mechanism is subjected in service.

The principal object of the invention is to provide a backstop constructed in a manner affording great strength without excessive weight, which may be reliably secured to the car sills with little labor and without difficulty, and in which the occurrence of shrinkage cracks and kindred manufacturing defects is minimized.

A further object of the invention is to provide a backstop construction well suited for use upon cars where the line of draft is low; and a still further object is to construct the backstop so that it may efficiently serve as a bolster center filler for transmitting the load of the car to the center bearing, thus preventing buckling of the webs of the adjacent car sills.

Generally stated, the principal feature of the invention consists in forming a backstop with side walls which are adapted to be secured to spaced car sills and are united at their forward ends to an end wall forming an abutment for a movable part of the draft rigging mechanism, a centrally disposed horizontally extending hollow column being united at its forward end to the said end wall and extending rearwardly therefrom, and the said column being connected rearwardly of said end wall to the side walls by oppositely disposed longitudinally extending webs and by a plurality of spaced transverse webs which themselves are united to the said oppositely disposed webs.

A further feature of the invention consists in forming the backstop with side walls and with a forward end wall forming an abutment for a movable part of the draft rig-

ging, and in supporting the said end wall against buffing shocks by means of a centrally disposed hollow column of oval cross section which is united at its forward end to said end wall.

Another feature of the invention consists in providing a backstop with side walls adapted to be secured to spaced car sills and with a forward end wall united to said side walls and adapted to form an abutment for a movable part of the draft rigging, a centrally disposed hollow column being united at its forward end to the end wall and being connected to the side walls by oppositely disposed horizontal webs, and a base plate being provided for the attachment of a center bearing, the horizontal webs being connected to the base plate by a transversely extending web, and the side walls of the said column to the rear of said transverse web being extended downwardly and directly united to said base plate in spaced relation to said side walls.

Still another feature of the invention consists in providing a backstop with a base plate and a top plate spaced vertically therefrom, the said backstop being adapted to be secured to spaced car sills having inwardly projecting flanges, and the said base plate and top plate being formed on opposite sides of the longitudinal axis of the backstop with faces adapted to engage and form seats for the opposed surfaces of the flanges of the car sills.

Other features of the invention, residing in particular details of construction and the relations of structural parts, will hereinafter appear.

In the drawings illustrating the invention, the scope whereof is pointed out in the claims,—

Figure 1 is a plan view of a backstop embodying the invention.

Figure 2 is a section on the line 2—2, Fig. 1.

Figure 3 is a section on the line 3—3, Fig. 1, looking in the direction of the arrows and showing the adjacent car sills in dotted lines.

Figure 4 is a view corresponding to Fig. 3 but looking in the opposite direction.

Figure 5 is a section on the line 5—5, Fig. 1.

The draft rigging (not shown) with which the backstop cooperates may be of any suitable form, such for example as that illustrated in the T. H. Symington Patent 5 No. 1,126,663, granted January 26, 1915. In this special form of draft rigging, which is to be regarded as merely illustrative, the buffing shocks to which the mechanism is subjected in service are communicated to 10 the backstop by the engagement of the rear end of the draft yoke therewith. The spaced center sills or draft sills 1 of the car may, in respect to some aspects of my invention, be of any form desired; but certain details 15 of construction are especially suited for co-operation with car sills having inwardly projecting flanges, and accordingly sills of that nature have been illustrated in the drawings.

20 The backstop is formed with longitudinally extending side walls 2 adapted to engage the inner faces of the neighboring sills 1, the forward parts of said side walls being preferably provided with two vertically spaced parallel rows of openings 3 for receiving rivets whereby the device may be rigidly secured to the car sills, and the rear portions of said side walls being of increased vertical extent and preferably equal 25 in height to the distance between the flanges of the respective sills 1. The increase in height of the rear portions of the side walls 2 not only enables the rivets by which the backstop is secured at its rear end to the car sills to be efficiently disposed for resisting 30 the tendency of the structure to rotate under buffing impacts but, as will herein-after appear, is also advantageous in relieving the weight of the sills 1 from buckling 35 strains due to the load of the car. As shown 40 in the drawings, the rivet openings 4 in the rear portions of the side walls 2 may be efficiently arranged in four spaced vertical rows, the greater number of said openings being disposed above the line of draft.

45 The forward ends of the side walls 2 are integrally united by a transversely extending vertical end wall 5 which is adapted to form an abutment for a movable part of the draft rigging, the portions of said side walls which are immediately adjacent the said end wall 5 being preferably convergent forwardly, as indicated at 6.

United to the end wall 5 and extending 50 rearwardly therefrom horizontally is a centrally disposed hollow column 7 which is preferably open interiorly from end to end. This column is integrally connected to the side walls 2 between their upper and lower edges by longitudinally extending horizontal webs 8 disposed on opposite sides of said column in the plane of the axis thereof. Rearwardly of said end wall 5 the backstop is provided above and below the horizontal webs 8 with a plurality of trans-

versely extending spaced webs 9 integrally uniting the said webs 8, side walls 2 and hollow column 7.

The hollow column 7 is preferably of oval cross section having its major axis vertical. 70 This form of column not only imparts great strength to the backstop in its longitudinal axis but affords ample space for the convenient driving of rivets and also produces a structure that is easily manufactured. 75

The floor plate or base plate 10 which is seated upon the usual center bearing (not shown) is directly united to the rear end of the hollow column 7 by extending the side 80 wall portions 11 of the rear end of said column downwardly in spaced relation so as to join with said base plate, the opening in the under side of the column thus provided between its side wall portions 11 affording a convenient means for removing the core 85 after the backstop is cast. The base plate is also preferably integrally united to the hollow column 7 by a transverse vertical web 12 which also is united to the horizontally 90 disposed webs 8 upon opposite sides of said column. If desired the downwardly extending side wall portions of the column 7 may be integrally connected by a vertically extending transverse web 13 whose upper edge 95 is preferably curved to conform to the interior of the column.

The top plate 14 and the bottom plate 12 of the backstop are spaced apart and braced vertically by means of a hollow tube or column 15 which is adapted to receive a king bolt (not shown). As illustrated in the drawings, the centrally disposed column 7 and the king bolt column 15 are directly united at the rear end of said column 7 105 and their interiors are in open communication with each other, thus enabling the backstop to be cast with a single core. In addition to the king bolt column 15 the base plate 10 and top plate 14, which are integrally connected to the side walls 2 of the backstop, may be braced in a vertical direction by a centrally disposed vertical web 16 united to the column 15 and to said plates and may also be braced by a plurality of 110 transversely extending webs 17 which extend between said plates and are integrally united thereto and also to the king bolt column 15 and the respective side walls 2 of the casting. Forwardly of the column 15 it is preferred to provide a centrally disposed vertical web 18 which unites the top plate 14 with the centrally disposed hollow column 7. As well shown in Figs. 3 and 4, the base plate 10 and the top plate 14 are formed on 125 opposite sides of the longitudinal axis of the backstop adjacent the side walls 2 thereof with inclined faces 19 which form seats for the inturned flanges of the respective sills 1 of the car, thus enabling the portion of the 130

backstop adjacent the king bolt column 15 to serve as a bolster center filler which prevents the webs of the adjacent car sills from buckling under load.

5. What I claim is:—

1. A draft rigging backstop comprising side walls adapted to be secured to spaced car sills, a forward end wall united to said side walls and adapted to form an abutment for a movable part of the draft rigging, a centrally disposed horizontally extending hollow column united at its forward end to said end wall and extending rearwardly therefrom, longitudinally extending webs on opposite sides of said column connecting the latter to said side walls, and a plurality of transversely extending spaced webs connecting said column, said side walls and said longitudinally extending webs rearwardly of said end wall.

2. A draft rigging backstop comprising side walls adapted to be secured to spaced car sills, a forward end wall united to said side walls and adapted to form an abutment for a movable part of the draft rigging, a hollow column united at its forward end to said end wall and extending rearwardly therefrom, and webs uniting said column to said side walls, said hollow column being of oval cross section.

3. A draft rigging backstop comprising side walls adapted to be secured to spaced car sills, a forward end wall united to said side walls and adapted to form an abutment for a movable part of the draft rigging, a hollow column of oval cross section united at its forward end to said end wall and extending rearwardly therefrom, horizontal webs extending toward the axis of said column and uniting said side walls to said column, and transversely extending spaced vertical webs uniting said column, said side walls and said horizontal webs.

4. A draft rigging backstop comprising side walls adapted to be secured to spaced car sills, a forward end wall united to said side walls and adapted to form an abutment for a movable part of the draft rigging, a centrally disposed hollow column united to and extending rearwardly from said end wall, and a base plate having a king-bolt opening therein, said column at its rear end being open on its under side and being provided with longitudinally extending side walls which are united to said base plate.

5. A draft rigging backstop comprising side walls adapted to be secured to spaced car sills, a forward end wall united to said side walls and adapted to form an abutment for a movable part of the draft rigging, a horizontally disposed hollow column united to and extending rearwardly from said end wall, a base plate to which the rear end of said column is united, a top plate spaced vertically from said base plate, and a verti-

cally extending hollow column uniting said base plate and said top plate and adapted to receive a king bolt, said columns being directly united integrally and having their interiors in open communication.

70

6. A draft rigging backstop comprising side walls adapted to be secured to spaced car sills having inwardly projecting flanges, a forward end wall united to said side walls and adapted to form an abutment for a movable part of the draft rigging, means extending between and connecting said side walls intermediate their upper and lower edges, a base plate integrally united to said side walls, a top plate spaced vertically from said base plate, and means extending between and integrally uniting said base plate and said top plate, said base plate and said top plate being formed on opposite sides of the longitudinal axis of said backstop with faces adapted to engage the flanges of said car sills.

85

7. A draft rigging backstop comprising side walls adapted to be secured to spaced car sills having inwardly projecting flanges, a forward end wall united to said side walls and adapted to form an abutment for a movable part of the draft rigging, a base plate located rearwardly of said end wall and integrally united to said side walls, and a top plate spaced vertically from said base plate and integrally united to said side walls, said base plate and said top plate being provided on opposite sides of the longitudinal axis of the backstop with faces adapted to engage the flanges of said car sills.

95

8. A draft rigging backstop comprising side walls adapted to be secured to spaced car sills, a forward end wall united to said side walls and adapted to form an abutment for a movable part of the draft rigging, a centrally disposed hollow column united at its forward end to said end wall and extending rearwardly therefrom, horizontal webs on opposite sides of said column connecting said column to said side walls, a base plate, and a transverse web extending between and connecting said horizontal webs to said base plate, the rear end of said column extending rearwardly of said transverse web and being spaced from said side walls.

110

9. A draft rigging backstop comprising side walls adapted to be secured to spaced car sills, a forward end wall united to said side walls and adapted to form an abutment for a movable part of the draft rigging, and a hollow column of oval cross section united at its forward end to said end wall, and extending rearwardly therefrom between said side walls, the major axis of said oval being vertical.
